UNITED STATES PATENT OFFICE.

DAVID C. BOYD, OF GALION, OHIO.

CULVERT.

No. 896,354.

Specification of Letters Patent.

Patented Aug. 18, 1908.

Application filed July 8, 1907. Serial No. 382,757.

To all whom it may concern:

Be it known that I, DAVID C. BOYD, citizen of the United States, residing at Galion, in the county of Crawford and State of Ohio, 5 have invented certain new and useful Improvements in Culverts, of which the following is a specification.

This invention has for its object a simple, durable and efficient construction of metallic 10 culvert, and the invention consists in certain constructions and arrangements of the parts that I shall hereinafter fully describe and claim.

For a full understanding of the invention 15 and the merits thereof and also to acquire a knowledge of the details of construction and the means for effecting the result, reference is to be had to the following description and accompanying drawings, in which:

20 Figure 1 is a perspective view of the culvert. Fig. 2 is a detail transverse section of the same. Fig. 3 is a detail view of a modification.

Corresponding and like parts are referred 25 to in the following description and indicated in all the views of the drawings by the same reference characters.

My improved metal culverts are constructed in sections of any desired length and diameter 30 and each section comprises a body portion 1 which is cylindrical and which is formed by rolling or shaping a metal sheet upon itself, the two ends or edges being preferably slightly overlapped to form the joint 35 in the completed cylindrical body portion.

Each body portion 1 is provided at each end with an outstanding collar 2, the body portions being placed end to end, as many as may be desired, to form a culvert of the requisite 40 length, the collars 2 being secured together by bolts or rivets 3 extending through abutting collars 2.

An important feature of my improved culvert resides in the provision of a series of reinforcing ribs 4, which extend longitudinally of each body portion, preferably from end to end, and which are of any desired number arranged on the exterior of the body portion 1 at any desired intervals or distances apart.

50 Each of these reinforcing ribs 4 is provided with outwardly projecting attaching flanges

5 secured by rivets 6 or the like to the sheet metal of which the body portion is formed, and between these attaching flanges 5 the 55 metal strips which form the reinforcing ribs 4

are crimped to produce longitudinally extending corrugations 7. The portions of the reinforcing ribs 4 between the attaching flanges 5 stand out preferably in a true radial direction from the body portion 1 of the culvert and the folds preferably abut against each other or are close to each other, as shown, so that the entire body portion is strengthened to a marked degree, while at the same time very light metal may be used 60 in the construction both of the body portion of the culvert and the reinforcing ribs thereof. Preferably the end collars 2 extend across the ends of the reinforcing ribs and abut against said ribs, so that the ends of the 65 ribs will serve to assist in strengthening the collars and prevent the same from bending. Preferably, also, one reinforcing rib is located at the joint of the overlapped ends or edges of the body portion and riveted or otherwise 70 secured on opposite sides of the joint as indicated in Fig. 2, so as to assist in maintaining a tight joint, it being noted that the inwardly extending middle crimp or bend of this rib 75 bears against the joint. 80

In the specific construction of the device illustrated in Fig. 1, the end collars 2 of the body portions 1 of the culvert are formed by bending outwardly the walls of the pipe. If desired, however, as illustrated in Fig. 3, 85 these attaching collars may be formed of a separate piece, as indicated at 2^a, bolted or otherwise secured to the ends of the body portions 1.

From the foregoing description in connection with the accompanying drawings, it will be seen that I provide a very light, durable and efficient construction of sheet metal culvert in which the ribs will effectively reinforce the body portion of the culvert and prevent the same from breaking down under very severe strain, while at the same time it is to be noted that the interior of the culvert is perfectly smooth and does in no wise impede the flow of water, which is not the case 90 with those sheet metal culverts in which the strengthening characteristic is produced by a series of circumferential corrugations formed in the body portion of the culvert itself. 95

Having thus described the invention, what 100 is claimed as new is:

A sheet metal culvert consisting of a body portion constructed of a sheet rolled upon itself and having its longitudinal edges locked together to form a joint, and reinforcing ribs 110

secured to the exterior of the body portion, the ribs being constructed of sheet metal and embodying outwardly extending attaching flanges, the ribs being crimped between the attaching flanges, whereby to produce outstanding and longitudinally disposed corrugations in the ribs, one of said ribs overlapping the joint in the body portion and having

an inwardly extending bend bearing against the joint.

In testimony whereof I affix my signature in presence of two witnesses.

DAVID C. BOYD. [L. s.]
